UNITED STATES PATENT OFFICE.

JOHN RZUCIDLO, OF SHENANDOAH, PENNSYLVANIA.

ICE SLIPPER.

Application filed May 19, 1927. Serial No. 192,563.

This invention relates to a new and useful device in the nature of an ice slipper particularly adapted to be attached to the shoes enabling the wearer to walk on or cross ice, 5 slippery snow, or the like, without injury due to slipping or falling.

The object of the invention is to provide an ice slipper of novel construction and arrangement of parts, hereinafter more fully 10 described, claimed and illustrated in the accompanying drawing.

Fig. 1 is a perspective elevational view of my improved ice slipper.

Fig. 2 is a perspective elevational detail 15 view of the front or sole member, as embodied in my improved device.

Fig. 3 is a similar view of the intermediate member.

Fig. 4 is a similar view of the upper heel 20 member.

Fig. 5 is a similar view of the lower heel member.

Fig. 6 is a fragmentary view, illustrating 25 a further development of my improved device.

Fig. 7 is a transverse sectional view taken on the line 7—7 of Fig. 6.

Fig. 8 is a fragmentary detail view illustrating a further development thereof.

30 As here embodied my improved ice slipper comprises sole members 10 and 11, preferably of flat metal, formed as at 12 and 13, curved so as to conform to the contour of the sole of a shoe, such as commonly worn

35 by people. The sole members 10 and 11 are provided with downwardly formed or bent elements 14 and 15, having formed therein apertures 16, adapted to receive both, or the like, as a means of attaching the sole members 10 and 11. The above described construction is such as will permit the sole members 10 and 11, to conform somewhat to the shape of the sole of the above mentioned shoe.

40 The sole members 10 and 11 have formed therein elongated longitudinal apertures adapted to slidably receive the enlarged extremities 18 of the intermediate members 19 and 20. The intermediate members 19 and 50 20 are provided with neck elements 21 formed by elongated transverse notches. The intermediate members 19 and 20 are provided with inwardly extended portions 23, positioned adjacent to the rear thereof, 55 and having formed therein elongated longitudinal apertures 23', registering with the

above mentioned elongated apertures, 17. The intermediate members 19 and 20 are provided with downwardly formed or bent rear elements 24 having formed therein 60 apertures 25, adapted to receive bolts, or the like, as a means of attaching the intermediate members 19 and 20, to the upper heel members 26 and 27, respectively. The said upper heel members are provided with 65 downwardly formed or bent front elements 28, having formed therein apertures 29, adapted to receive the latter mentioned bolts.

The upper heel members 26 and 27 are 70 provided with downwardly formed or bent elements 30, having formed therein apertures 31, adapted to receive bolts, or the like, as a means of attaching the said upper heel members 26 and 27. The upper heel members 26 and 27 have formed therein elongated longitudinal apertures 32.

The lower heel members 33 and 34 are formed as at 35 and 36, curved so as to conform to the contour of the heel of the above 80 mentioned shoe, and have formed therein elongated longitudinal apertures 37.

The above mentioned sole members 10 and 11, the intermediate members 19 and 20, the upper heel members 26 and 27, and the lower 85 heel members 33 and 34, have attached thereto, and extended downwardly therefrom spike members 38, having pointed lower extremities adapted to grip ice, snow or the like.

The sole members 10 and 11, the intermediate members 19 and 20 and the lower heel members 33 and 34, are provided with upwardly formed elements 39, having formed therein elongated apertures 40, 95 adapted to receive flexible members, straps, or the like, provided with the usual conventional buckles, as a means of removably attaching my improved ice slipper to the shoe of the wearer.

100 The above described construction is such as will permit the sole members 10 and 11, and the lower heel members 33 and 34 to be held in any desired extended position, so as to fit the shoe of the wearer, by means of the bolts, 41 and 42, positioned in the elongated apertures 17, 23, and 32, 37, respectively.

In Figs. 6, 7, and 8 of the accompanying drawing, I have shown engaging members 43, of disc shaped construction, secured to 110 the sole members 10 and 11, and to the upper heel members 26 and 27. The engaging

members 43 are provided with downwardly extended tapered elements 44, adapted to engage in any desired manner one of the tapered recesses formed in the intermediate members 19 and 20, and the lower heel members 33 and 34, as a means of more securely holding the above mentioned and described elements in any desired extended position for the purpose as hereinbefore set forth.

Having thus described my invention, what I claim as new and desire to protect by Letters Patent of the United States is as follows:

1. A device of the class described comprising spaced apart lower heel plates having outer curved edge portions adapted to be independently positioned for registering the edge portions thereof with the edges of a heel, attaching members adjustably mounted on each of said independent heel plates, intermediate connecting sections attached at their rear extremities to said attaching members, sole plates joined at the adjacent edges and adjustably attached to the forward ends of said connecting members, and spikes on the lower surface of said sole plates, heel plates and connecting members.

2. A device of the class described com-

prising a pair of lower heel plates having longitudinal apertures therein and outer curved edge portions and adapted to be independently positioned for registering the edge portions thereof with the edges of the heel of a shoe, an attaching member comprising a plate having a longitudinal aperture therein adapted to register with the slots of said heel plates, bolts disposed through said apertures for adjustably securing said heel plates and attaching member together, downwardly disposed flanges on the forward ends of said attaching member having apertures therein, connecting members attached to the flange of each of said attaching member, individual sole plate sections having longitudinal apertures therein slidably mounted on the forward extremity of said connecting members, the forward extremities of said connecting members being disposed upwardly through the longitudinal slots of said sole plate sections for adjustably attaching the same together, and spikes on the lower surfaces of said heel plate, sole plate and connecting members.

In testimony whereof I have affixed my signature.

JOHN RZUCIDLO.
